UNITED STATES PATENT OFFICE.

RUDOLPH O. TRUEB, OF MURRAY HILL PARK, NEW JERSEY.

EMBROIDERY-FRAME.

1,335,806.

Specification of Letters Patent.

Patented Apr. 6, 1920.

Application filed August 16, 1919. Serial No. 317,974.

To all whom it may concern:

Be it known that I, RUDOLPH OTTO TRUEB, a citizen of the United States, and a resident of Murray Hill Park, county of Union, 5 and State of New Jersey, have invented certain new and useful Improvements in Embroidery-Frames, of which the following is a full, clear, and exact specification.

My invention relates to implements for 10 embroidering fabrics, and consists in devising the herein shown and described improvement in frames for stretching the fabric, whereon the embroidery is to be applied.

15 The improvement is illustrated in the accompanying drawings, wherein—

Figure 1 is a plan view of one of the grooved bars of an embroidery frame, to 20 which the fabric, whereon the embroidery is to be applied, is attached;

Fig. 2 is a longitudinal section thereof on line 2—2, indicated in Fig. 1;

Fig. 3 is a cross-sectional view thereof on line 3—3, indicated in Fig. 1;

25 Fig. 4 is a plan view of a rope, made of twisted strands of soft fibrous material and corresponding in its dimensions with the dimensions of the groove in the bar;

Fig. 5 is a fractional plan view of the 30 proved frame, showing the manner of securing thereto a piece of the fabric, whereon the embroidery is to be applied, and

Fig. 6 is a cross-sectional view on line 6—6, indicated in Fig. 5.

35 Embroidery frames are usually composed of four bars, two so-called main-bars, provided with means for attaching thereto of the fabric, whereon the embroidery is to be applied, and two side-bars along which one 40 or both of the main-bars are movable and securable thereto in adjusted position, *i. e.* at such distance apart as the work requires. One of the main-bars, designated by the reference letter *a* is shown in Fig. 1, wherein 45 also the side-bars *b* and *b'* are shown, inserted in the slots *c* (see Fig. 2). The main-bar *a* is shown as it is held in position, relatively to the side-bars *b* and *b'*, by pins *f* inserted through the registering perforations *f'* in the main-bar *a*, and the perforations *e* in the side-bars. The other main-bar (not shown) is similarly equipped, and 50 in a likewise connected to the side-bars.

The main-bars *a* are grooved as shown at *i*

and provided with the toothed metallic 55 strips *g*, secured thereto by screws or nails *h*. The teeth, or prongs *g'* project into the groove *i*, and are slightly deflected downward as shown in Fig. 6, to avoid the danger of the fabric or the operator's hands 60 coming accidentally in contact therewith.

Embroidery is often required to be applied to soft, open weave fabrics, and to enable such tender fabrics to be stretched upon the frame and protected against injury by a greater strain upon some part of it, I have devised the rope *v*, corresponding in thickness to the width of the groove *i*, and which is used to bend or fold the fabric thereon, and then press the rope, with the 70 bend or fold of the fabric thereover, into the groove *i* and against the prongs *g'*. This rope *v* is made of twisted strands of soft fibrous material, preferably softly twisted strands of cotton, tied together by 75 windings *w* at the ends.

By these means the operator is enabled to fasten the fabric more evenly stretched laterally to the bar *a*, and the strain thereon is not only more evenly distributed throughout its entire width, but is also taken up, to a considerable extent, by the rope *v* over which the fabric is bent or folded, the prongs *g'* penetrating the twisted strands of the rope *v* when the same with the fabric bent 80 or wound thereon is pressed into the groove *i*. The ends of the rope *v* may be inserted into the holes *d* at the ends of the groove *i*, and secured therein by pushing in the round-headed and blunt-pointed pins *y* into 85 the bores *z* as shown in Figs. 1 and 5, respectively.

The use of this rope *v* also renders the operation of stretching the fabric upon the frame easier, in that it enables the operator 95 to perform this operation by merely spreading the fabric laterally, laying the rope thereon, bending the fabric over the rope and then pressing the rope, while holding the edges of the fabric bent over it, into 100 the groove *i*, and against the prongs *g'*. The same operation is then repeated to attach the fabric to the other main-bar. The lateral spreading of the part of the fabric thus stretched between the main-bars may 105 then, if necessary, be effected by the devices shown and described in the U. S. Letters Patent No. 1,299,873, granted to me April 8,

1919, whereby the fabric is affixed to, and stretched between, the main-bars as evenly as it is feasible to do.

I claim as my invention:

1. In a frame for stretching fabrics, a bar provided with a longitudinal groove, a row of prongs arranged along one edge of said groove and extending into the same, and a rope-like member of soft fibrous material fitting into said groove and engaged by said prongs, whereby a piece of fabric bent or folded on said member in the groove is securely held therein.

2. In a frame for stretching fabrics, a bar provided with a longitudinal groove, a row of prongs arranged along one edge of said groove and extending into the same, a rope-like member of soft fibrous material fitting into said groove and engaged by said prongs,

whereby a piece of fabric bent or folded on said member in the groove is securely held therein, and means for securing said rope-like member in said groove.

3. In a frame for stretching fabrics, a bar provided with a longitudinal groove and 25 with a hole at each end of the groove, a row of prongs arranged along one edge of said groove and extending into the same, a rope-like member of soft fibrous material fitting 30 into said groove and engaged by said prongs, whereby a piece of fabric bent or folded on said member in the groove is securely held therein, and means for fastening the ends of said member in said holes.

RUDOLPH O. TRUEB.
